Patented Aug. 27, 1918.

UNITED STATES PATENT OFFICE.

ALFRED W. HARRIS, OF PEORIA, ILLINOIS.

HEADLIGHT.

1,276,757.

Specification of Letters Patent. Patented Aug. 27, 1918.

Application filed April 24, 1916. Serial No. 93,098.

To all whom it may concern:

Be it known that I, ALFRED W. HARRIS, a citizen of the United States, and a resident of Peoria, in the county of Peoria and State of Illinois, have invented new and useful Improvements in Headlights, of which the following is a specification.

This invention has reference more particularly to head lights which are provided with means whereby the direction in which the light is projected may be adjusted, and is particularly applicable to the headlights of automobiles, although its use is not necessarily confined thereto, but it may be used in any case where it is desired to adjust the direction in which the light is projected.

The object of this invention is to provide means for changing the direction in which the light is projected without moving the entire lamp structure, such means being capable of operation at the lamp or at a distance therefrom.

A further object is the provision of adjustable reflecting means which may readily be mounted in the standard headlight without difficulty, and which does not require a special lamp structure to use.

A further object is the construction of an attachment for standard head lights for changing the direction of projection of the light, said attachment being designed so that all the working parts are mounted on the attachment in complete working condition so that the attachment may be inserted in position in the lamp, complete and ready for operation without the necessity of connecting any of the working parts to the lamp casing or structure and making adjustments incident thereto.

A further object is the mounting of the movable parts of the reflecting means, by means of a spring holder so that the movable parts are held firmly in position at a tension so as to take up any wear and also prevent rattling which is likely to develop if otherwise held, particularly when used on vehicles.

A further object is the use of flexible means for communicating control to the lamp, such means being employed so as to permit twisting and straining incidental to the use of the lamps on vehicles, without affecting the operation of the controlling means, and also

being employed so as to enable the lamp and control mechanism to be readily and easily mounted without complicated control mechanism.

The invention also has other objects which will appear from the following specification and which are particularly pointed out in the claims.

In the accompanying drawings which illustrate my invention Figure 1 is a sectional view, the upper half of which is taken on the line A—A of Fig. 2, and the lower half of which is taken on the line B—B of Fig. 2; Fig. 2 is a fragmentary view of the rear of the reflector showing the manner of mounting the movable reflector on the supporting rim or shell; Fig. 3 is a view of control levers which may be provided for operating the reflector; Fig. 4 a sectional view taken on the line C—C of Fig. 3 showing the manner in which the control levers are mounted on the dash of an automobile; Fig. 5 is a rear view of the control levers showing the lever arms which are provided on the opposite side of the dash for connection to the control wires; Fig. 6 is an enlarged view taken substantially on the line D—D of Fig. 1 showing the manner of connecting the control wires to the reflector; and Fig. 7 is a sectional view taken on the line E—E of Fig. 6.

In the drawings, 1 represents the usual outer shell or lamp body with which headlights are commonly constructed, and 2 the door frame which is usually hinged to the shell 1 and may be opened to provide access to the interior of the lamp. This door frame has an annular abutment 3 against which the glass 4 is set and there is an annular groove 5 in the frame 2 immediately back of the annular abutment 3 into which a spring wire 6 may be snapped for the purpose of holding the glass 4 in position. The reflector is usually mounted so that it may be easily removed, and for this purpose screws may be employed or it may be held with the same device that holds the glass by providing the reflector with an annular flange 7 which is placed against the rim of the glass 4 and has the spring wire 6 inserted back thereof, so as to hold the reflector and the glass 4 at the same time in position. In my construction the entire re-

reflector is not made in one piece but a partial reflector 8 is provided and secured to the lamp by means of the flange 7 as is customary when a full reflector is used. This construction enables my new device to be readily mounted in an old lamp by merely removing the old reflector and placing the new reflector in place with the same means that is employed to hold the old one.

10 In conjunction with the partial reflector 8 I use a movable reflector 9 which projects within the partial reflector 8 sufficiently so that a complete reflecting surface is provided by means of the over-extending portions of the partial reflector 8 and the reflector 9 in any position in which the reflector 9 may be adjusted. The curve of the partial reflector 8 is so constructed that the edge 10 of the reflector 9 will fit very close thereto in any position in which the reflector 9 is adjusted so that a forward view at any time will show only a line where the two reflecting surfaces meet.

For mounting the reflector 9 in a movable relation with the partial reflector 8 there are provided four springs 11 having an end secured to the rear face of the reflector 9 as at 12 at a distance from the front edge 10 so as to permit reception of the wall 20 of the partial reflector 8 between the spring 11 and the wall of the reflector 9 as the reflector 9 is adjusted in its various positions. At the forward end of each spring 11 is a holder 13 which contains a ball 14 loosely mounted therein so as to continuously bear against the rear face of the partial reflector 8 and roll readily thereon. It will be observed that the relation of the springs 11 to the surface of the partial reflector 8 against which it bears is such that the reflector 9 is constantly held in the rear-most position very close to the partial reflector 8 and the mounting of the reflector 9 by means of the balls leaves the reflector perfectly free 45 to be moved or turned in any direction.

For operating the reflector 9 in a universal manner, it is provided with two connections thereto at a 90 degree interval, one of which is arranged to give to the reflector an up 50 and down movement and the other of which a lateral movement, the combined effect of which two movements will give the reflector a movement not only up and down and lateral, but at any desired angle. For operating this reflector as desired at a distance, I employ what is known as Boden wires, comprising a tube 15 containing a steel wire 16 said tube 15 furnishing a flexible container within which the wire 16 may 60 be moved lengthwise. At the point where the wire 16 is to be connected with the reflector 9 the surface of the reflector 9 may be raised as at 17 and formed so that it will fit closely to the edge of the partial reflector 8 in any position, and there are pro-

vided rollers or balls 18 which are mounted in bearings 19 at the edge of the partial reflector 8 and the said rollers or balls bear against the rear face of the reflector 9 so as to prevent displacement of the said reflector when power is applied for adjusting it. Intermediate of the rollers 18 is a bearing block 20 which supports the inner ends of the rollers 18 and is provided with an opening 21 within which the end of the tube 75 15 is held by means of the set screw 22 and lock screw 23. The wire 16 is connected to the rear face of the reflector 9 at a distance from the edge 10 thereof to permit the required adjustment of the reflector and this 80 connection is made by means of a ball bracket 24 on the reflector and a socket 25 on the end of the wire 16 which engages the ball bracket 24 and permits free universal movement. For operating the reflector at 85 a distance, various means may be provided, one of which I have shown consisting of two levers 26 and 27 which may be mounted on the dash 28. On the opposite side of the dash are complementary levers 26^A and 27^A 90 which are connected to the ends of the wires 16. These levers, as is apparent, move in an arc and at one side of the bearing plate 28 for the levers, is a clamp plate 29 whereby the ends of the tube 15 of the wires 16 are 95 secured to the plate, the projecting ends of the wires being adjustably connected to the complementary lever 26^A and 27^A by means of set screws 30 so that the movement of the said levers will force the wires in and out 100 of the tubes, and by the connection of the wires at the opposite ends will operate the reflector 9. One of the levers 26 may be provided for adjusting the reflector in the lateral direction and the other lever 27 for 105 adjusting the reflector in a vertical direction and the combined movement of the levers will swing the reflector in directions other than the vertical and lateral thereby giving to the reflector a universal movement which 110 will project the light in any direction at the will of the operator within such limitations as may be provided in the construction of the device.

What I claim is:

1. In a device of the class described, the combination of a lamp body; a reflector wholly within said lamp body and comprising a plurality of parts, one of said reflector parts being fixed in but removable from said lamp body and the other reflector part being universally mounted on the fixed part of the reflector, and means for holding said reflector parts in operative engagement with each other.

2. In a device of the class described, the combination of a lamp body with a light opening therein, a flange adjacent the light opening, an adjustable reflector, a stationary part provided with means for detachably

securing the stationary part to the said flange, and means for supporting the adjustable reflector on the stationary part so that the reflector is universally movable.

- 5 3. In a device of the class described the combination of a lamp body, a removable reflector structure in said lamp body comprising a movable reflector and means for supporting said reflector so as to be universally movable, means mounted on said structure and operating independently of the lamp body for moving the reflector, and means for detachably securing the reflector structure in the lamp body.
- 10 4. In a device of the class described the combination of a lamp body, a removable reflector structure in said lamp body comprising a stationary part, means for detachably securing the stationary part to the lamp body, a movable reflector, means for supporting the said reflector on the stationary part so as to be universally movable, and means for operating the said reflector said means having a bearing on the said stationary part and a power member attached to the movable reflector.

5. In a device of the class described the combination of a lamp body, a stationary part, means for detachably securing the stationary part to the lamp body, an adjustable reflector, means for supporting the adjustable reflector on the stationary part so that the reflector is universally movable, a tubular member mounted on the stationary part and an operating member movable lengthwise in the tubular member and connected to the movable reflector.

6. In a device of the class described, the combination of a lamp body, a reflector in said lamp body comprising a plurality of parts, one of said parts being fixed with respect to the lamp body and the other of said parts being universally movable on said

fixed part, and resilient means for holding the movable part of said reflector in operative position upon the fixed part of said reflector.

7. In a device of the class described, the combination of a lamp body, a reflector in said lamp body comprising a plurality of parts, one of which has universal bearing with respect to the other, and co-acting means on said reflector parts for yieldingly holding said reflector parts in operative engagement with each other.

8. In a device of the class described, the combination of a lamp body closed at one end by a substantially flat glass, a reflector in said lamp body back of said glass, said reflector comprising a plurality of parts, one of said reflector parts being fixed with respect to the lamp body and the other reflector part being universally movable on said fixed part, and coacting means on each of said reflector parts for limiting the universal movement of said movable part of the reflector on said fixed part of the reflector.

9. In a device of the class described, the combination of a lamp body, a reflector in said lamp body comprising a plurality of parts, one of said reflector parts being fixed in but removable from said lamp body and the other reflector part being universally mounted on the fixed part of the reflector, an actuating device located at a place remote from the lamp body, a flexible casing extending from within said lamp body to said actuating device, and means in said flexible casing operatively connected at one end to the universally movable part of the reflector and at the other end to said actuating device.

In testimony whereof I have hereto affixed my signature.

ALFRED W. HARRIS
